UNITED STATES PATENT OFFICE

JOHN DELLWO, OF FOREST LAKE, MINNESOTA

ANTICREEPER FOR RAILWAY RAILS

Application filed June 25, 1930. Serial No. 463,730.

This invention relates to a device for preventing railway rails from creeping.

It is an object of the invention to provide a device of this character which can be applied readily to a rail and, when properly secured thereto, will bear against one side of an adjacent tie so that any tendency of the rail to creep or move longitudinally will be offset by the pressure of the device against the tie.

Another object is to provide a device of this character which can be made readily and has combined with it a means for supporting the head of the rail, and for preventing the device from shifting relative to the rail.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope 25 of what is claimed without departing from the spirit of the invention.

In the accompanying drawings the preferred forms of the invention have been shown.

In said drawings

Figure 1 is a section through a rail having the anti-creeping device attached thereto.

Figure 2 is a side elevation thereof.

Figure 4 is a section on line 4—4, Figure 3, modified form.

Figure 4 is a section on line 4—4, Figure 3.

Figure 5 is a perspective view of a heavy type of anti-creeper.

Figure 6 is a similar view showing a modification thereof.

Figure 7 is a perspective view of another form.

Figure 8 is a section through a rail provided with an anti-creeper which does not have an integral brace.

Referring to the figures by characters of reference, 1 designates the base of the device which is shaped to straddle and fit snugly on one of the base flanges A of a rail, the web and head of which have been indicated

at B and C respectively. This base has its underlying portion 2 increased in thickness toward one end so as to provide an extensive abutment 3 adapted to bear against one side of a tie T. A set screw 4 extends 55 into the base at a point where it will engage the upper surface of flange A close to the web B.

A brace 5 can be made integral with the base 1 and extends upwardly therefrom. 60 This brace is so shaped and proportioned as to fit snugly against the web B and the bottom of head C so as to constitute a support for the head.

If desired, the outer surface of the underlying portion of the device can be waved or corrugated as indicated at 6 in Figure 3, and the brace 7 can be similarly shaped. In this way metal is added in the form of ribs which materially strengthens the device and adapts 70 it for heavier use. In the structure shown in Figures 3 and 4 the lower edge of the underlying portions leading to the abutment 8 is also waved. Thus this portion will better engage the ballast between the ties and 75 assist in holding the device against creeping.

It is not essential that the brace be made waved or corrugated. Instead it can be rounded from side to side as shown at 9 in Figure 5 or can be made flat as shown at 10 in Figure 6. Furthermore, instead of providing a single set screw 4, two of these screws can be employed as shown at 11 in Figure 5. In Figure 7 the base 12 has been shown merging along curved lines into a relatively light 85 brace 13, but it is to be understood that under some conditions the brace can be eliminated entirely as shown for example in Figure 8 wherein the base 14 has its inner side bearing against web B which is exposed above the 90 base.

In the structures illustrated in Figures 5 and 6 the underlying portions 15 are provided with pronounced ribs 16 at the sides thereof of which, with the waved lower edge 17, insures an intimate connection between the device and the ballast portions of which will be seated in the channels 18 formed between the ribs.

In every instance the underlying portion of 100

the device includes an abutment for bearing against one face of the adjacent tie.

By providing braces extending to the head of the rail there is no danger of the device 5 rocking and creeping laterally relative to the rail, because any lateral pressure due to side tilting of the rail will be transmitted to the brace and the attachment will thus move bodily with the rail during such tilting or 10 lateral distortion.

10 What is claimed is:

An anti-creeping attachment for railway 15 rails including a base adapted to straddle and fit snugly upon a base flange of a rail, said base having a depending underlying portion increasing in size toward one end to constitute a tie-engaging abutment, means carried by the base for gripping the base flange of the engaged rail, and a brace integral with 20 the base for bearing snugly against the web and head of the engaged rail, the brace and base being of equal length and there being depressions in the underlying portion of the base and in the brace for the reception of 25 ballast, the depressions in the brace being extended from the top to the bottom thereof, and the depressions in the underlying portion being extended transversely thereof.

In testimony that I claim the foregoing as 30 my own, I have hereto affixed my signature.

JOHN DELLWO.
